(57) **CLAIM**

The ornamental design for a shampoo bottle, as shown and described.

DESCRIPTION

FIG. 1 is a perspective view of a shampoo bottle;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line is included solely for the purpose of defining the bounds of the claim in FIG. 7. The broken line itself is not claimed.
